[57] **CLAIM**

The ornamental design for a clothes hanger, as shown and described.

DESCRIPTION

FIG. 1 is a perspective view taken from the front of a hanger in accordance with our design;

FIG. 2 is a front elevation thereof, the rear view being a mirror image thereof;

FIG. 3 is an end view of the hanger shown in FIG. 1;

FIG. 4 is an end view taken from the other end thereof of the hanger;

FIG. 5 is a bottom view of the hanger;

FIG. 6 is a top plan view of the hanger of the present design;

FIG. 7 is a perspective view of a second embodiment of the design of FIG. 1, the only difference being the addition of a third hook within the hanger body;

FIG. 8 is a front elevation of the embodiment of FIG. 7, the rear view being a mirror image thereof; and,

FIG. 9 is an enlarged cross-section taken through line 9—9 of FIG. 8, this cross-section being the same in both embodiments.
